(57) **CLAIM**

The ornamental design for the sensor mote, as shown and described.

DESCRIPTION

FIG. 1 is a perspective view, taken from the top, of a sensor mote according to an exemplary embodiment of the present invention;

FIG. 2 is a perspective view, taken from the bottom, of the sensor mote of the embodiment of FIG. 1;

FIG. 3 is a top plan view of the sensor mote of the embodiment of FIG. 1;

FIG. 4 is a front elevational view of the sensor mote of the embodiment of FIG. 1;

FIG. 5 is a rear elevational view of the sensor mote of the embodiment of FIG. 1;

FIG. 6 is a right-side elevational view of the sensor mote of the embodiment of FIG. 1;

FIG. 7 is a left-side elevational view of the sensor mote of the embodiment of FIG. 1; and,

FIG. 8 is a bottom plan view of the sensor mote of the embodiment of FIG. 1.
